UNITED STATES PATENT OFFICE.

BENJAMIN F. ORTON, OF EAST SAGINAW, MICHIGAN.

DYNAMO-ELECTRIC MACHINE OR MOTOR.

SPECIFICATION forming part of Letters Patent No. 331,818, dated December 8, 1885.

Application filed February 11, 1885. Serial No. 155,626. (No model.)

To all whom it may concern:

Be it known that I, BENJAMIN F. ORTON, a citizen of the United States, and a resident of East Saginaw, in the county of Saginaw and State of Michigan, have invented certain new and useful Improvements in Dynamo-Electric Machines or Motors, of which the following is a specification.

The object of my invention is to simplify and improve the construction of dynamo-electric machines and motors, as also to secure compactness, and likewise freedom from heating of the armature while the machine is in use.

My invention consists in the improved details and the particular combinations that will be described in connection with the accompanying drawings, and will then be more specifically designated in the claims.

In the accompanying drawings, Figure 1 is a side elevation of a dynamo machine or motor constructed in accordance with my invention. Fig. 2 is an end elevation of the same. Fig. 3 is a plan of the machine. Fig. 4 is an enlarged view of the armature, showing the same in side elevation with a portion in vertical section. Fig. 5 is an elevation of the armature-core detached. Fig. 6 is a vertical cross-section of the spider or frame supporting the armature-core, and illustrates certain details of construction, to be described further on. Fig. 7 is a plan of a portion of the armature, and shows one of the shoes, of iron, placed between the coils or bobbins on the armature. Fig. 8 is a perspective view of the separating-pieces applied to the outer circumference and to the side of the armature-core between adjoining bobbins. Fig. 9 is a perspective view of my improved spool, upon which the coils of the armature are wound, and which is adapted after the winding to be slipped into place upon the armature core or body. Fig. 10 is a central cross-section of the armature-core shown in Fig. 5. Fig. 11 is a plan of a portion of the armature-core at the point where it engages with one of the arms of the spider or frame on which it is supported.

Referring to Figs. 1 and 2, A indicates the base or pedestal of the machine, which pedestal is made of iron, and is formed or pro-

vided at its upper side with one of the pole-pieces, N, of the machine. The pedestal is widened out at A² into a base-plate, which is secured by bolts or otherwise to a foundation, 55 A³, of wood or other suitable material. Projecting from the side of the iron pedestal are longitudinal extensions A⁴, upon which rest or to which are secured the upright field-magnets B B, wound in any suitable manner with 60 the coils complete, as shown at the left, or in sections, as indicated at the right, of the figure. The cores of these magnets rest upon and are in connection with the extensions A⁴, so that the magnetism excited by the coil may be imparted to the pole-piece N. It is of course 65 to be understood that the coils are wound or connected so as to conspire in producing the same polarity north or south, as the case may be, in the pole-piece N. Secured to the top 70 of the magnets B B, and in magnetic connection with their cores, is a plate or plates, C C, of iron, joining the tops of the magnets, and formed or provided at S with a pole-piece suitably curved or grooved to form in 75 conjunction with the pole-piece N a circular magnetic field for an annular armature. The poles N S lie, as indicated, in the line connecting the two magnets B B, and the whole form a magnetic parallelogram, the two sides of which consist of the magnets, while the top and bottom are formed of masses of iron constructed or provided at points between the magnets with pole-pieces. The plate C is secured to the top of 80 the magnet-cores by bolts and nuts, (indicated 85 at G²), said bolts passing down through the perforated cores of the magnets, and having their heads located beneath plates A, while the nuts of the said bolts are on the top of the plates G. This feature of construction is not 90 herein claimed, as it forms the subject of claims in a prior application for patent filed by me February 4, 1885, No. 154,895. The pole-pieces N S are curved and grooved to fit the two sides and outer periphery of an annular armature, the construction of which will be more fully described hereinafter. In this form of field-magnet it will be observed that the pedestal or base coincides magnetically 95 with the lower pole-pieces, and therefore tends 100 to assist in the formation of magnetic polarity at the proper point. This form also gives

simplicity and economy in the use of material, since but one support is used for the field-magnet, and the material of that support may in part constitute the mass forming the pole-piece.

D indicates a shaft for said armature, which shaft runs in the journals or bearings supported upon brackets D², which latter are suitably secured to the lower pole, N.

10 The commutator of the machine is indicated at E, and is of any desired or ordinary description. In order to further steady the machine while in operation, braces A⁵ may be applied, as indicated, between the base A³ and the extension A⁴. By this construction of the field-magnet good magnetic effects are obtained from a small amount of iron, while at the same time the construction is exceedingly compact and simple. The arms of a spider-frame, upon 15 which the core of the armature is supported, are indicated at F. These arms extend radially from a central hub, F², and terminate at their ends in bifurcations, forming a seat for the armature-core. The forks or bifurcations are indicated at F³, Fig. 6.

The armature-core is a sectional one, this construction being adopted in order to permit the bobbins or coils thereof to be slipped into place after being wound around a suitable coil or spool. I build up the body of the armature from thin plates or sheets of iron, included, preferably, between two retaining-bands.

30 The method of forming the sectional armature, which I will now describe, might be carried out with other forms—as, for instance, with those in which the body is made up from wires suitably secured together.

35 Referring to Fig. 5, G indicates a ring or band of iron forming a support or inner retaining-band, for the body for the armature, while G² is an outer retaining-band. Both of these bands are somewhat thicker than the thin sheets of iron forming the body or central 40 portion of the core, so as to give the requisite stiffness or stability to the structure. The bands G G² may be formed of continuous pieces of iron, if so desired; and this is the preferable way of making the inner band.

45 In building up the armature, I wind or form around the annular plate G a series of thin plates of iron, H, which may be a continuous sheet or band, or may be made up by joining or overlapping several sections of thin sheet-iron.

50 The thin plates or sheets H are separated from one another at suitable points by pieces of iron, or any other desired material, (indicated at H²), so as to leave free air-space extending laterally through the armature, to permit 55 ready circulation of air for the purpose of keeping the armature cool. The outer retaining-band, G², is made of iron, and through it pass rivets, (indicated at G³), which extend through the body of the armature and the inner plate, G, so as to bind the whole firmly together. Having formed a continuous ring

or body of iron in this manner, I divide the same into one or more sections by means of a suitable cutter, and then, after placing the abutting ends of the two sections thus formed 70 firmly together and securing them in this position, I place the armature in a lathe and turn it down in its inner and outer peripheries to a true circle, this being done in order to compensate for the material removed in the process 75 of bisecting the annulus. The core may now be again taken apart and the armature coils or bobbins applied by slipping them into place upon it, after which the whole is secured in position upon the spider or frame by the devices to be presently described. It is preferable to divide the armature on a line through the separating-pieces H², since when the latter are made of iron a better magnetic joint will be formed.

80 In order to hold the core firmly in place upon the spider, I have devised the following construction: At suitable points upon the core-sections where they rest upon the spider-arms I cut grooves or slots in their sides, as indicated at I, Fig. 11, so as to form offsets, which will impinge against the sides of the spider-arms and prevent the core from moving circumferentially in its support. It is of course to be understood that the body or core of the 85 armature is somewhat wider than the open space between the bifurcations F³, the excess of width being indicated by the dotted lines, Fig. 6, which show the width of the outer and inner retaining-bands, G G². In the Figs. 4 90 and 6 only the inner and outer retaining-bands of the armature-core are shown, in order that the construction may be better seen. The core-sections are slipped into place upon the ends of the spider-arms, which latter fits snugly 95 in the grooves or slots I. To hold the armature-core in place against centrifugal action, a bolt or screw, K, may be employed, which bolt passes through the armature core or body 100 in a radial direction into the spider-arm. 105 The bolt or screw K is held firmly in place by the bolt K², which extends across from one arm, F³, to the other immediately over the head of the screw K'. The bolt K² has the additional 110 function of holding in place one of the supporting pieces of iron applied to the exterior 115 periphery of the armature-core between the armature coils or bobbins.

120 Separating-pieces of iron applied to the exterior periphery of the armature-core between the armature-bobbins are constructed as follows:

125 M indicates a shoe or plate, of iron, preferably curved to the form of the armature, and provided with the two radially-extending sides M², attached to or cast in one piece with the base M. Mounted upon the shoe, and substantially filling the space between the sides, is a series of the plates R, set on edge 130 and secured by bolts or rivets passing transversely through the sides M² and the plates R. The plates are kept a short distance apart by

washers or blocks R^2 upon the bolts or rivets used for this purpose, as indicated at a . The latter serve the additional function of holding in place the pieces of iron that are attached 5 to the side of the armature between the adjoining bobbins. The separating-pieces on the side of the armature are made up, preferably, of two series of plates, S , which overlap one another at their inner ends, nearer to the inner side of the armature, and diverge, as indicated, on the sides of the bobbins. At their outer ends, where bolts a pass through them, they are separated by pieces of iron or other material, so as to leave free air-spaces between 10 them. These plates may be of any desired shape, and may be broader or narrower, according as it is desired to more fully fill up the space on the sides of the armature between the bobbins. If desired, they might be 15 held by bolts or rivets separate from the bolts A . At the points where they overlap the bolts or rivets pass into or through the inner retaining-band, G , or might, if desired, pass under the same. At the points over the 20 spider-arms the bolts K^2 assist in holding the upright plates R together. At these points the sides M^2 of the shoes are cut away, as indicated at M^4 , Fig. 6, so as to fit down over the forked end of the spider-arm. The shoes 25 M might be held down by screws, as indicated in Figs. 4 and 7, passing into the outer retaining-band, G^2 . Extending circumferentially from the base M of the shoe, and in both directions, are the projections or toes L^2 , that 30 pass beneath the spools T upon which the coils are wound, and between the body of the same and the armature-core, so as to hold the spools or bobbins firmly against the movement, and to also hold the shoes in place against centrifugal action. To assist in the interlocking of 35 the bobbins and the supporting-pieces on the outer periphery of the core, the spools T may be formed with projections, (indicated at T^3), which enter corresponding depressions in the side plates, M^2 M^4 , and the plates R . 40 The spool upon which the coils are wound is constructed, preferably, as shown in Fig. 9, and consists of two plates, W , on opposite sides of the space filled by the armature-core, 45 and which plates are joined in the spool heads or flanges V . The plates W are straight, instead of being curved to the form of the armature, and the flanges or heads V are substantially parallel, so as to form space for the 50 bobbins that are of substantially the same capacity upon the inside and outside of the armature-core. The difficulty that ordinary arises from the crowding of the coils upon the 55 inside of the annular armature is thus avoided. 60 The distance between the plates W must of course be somewhat greater than the thickness of the armature-core in a radial direction, in order to permit the spools to be slipped in place upon the core sections. To fill up the space on 65 the inside of the plates W and the body of the core, plates of iron may be inserted, as indi-

cated in section at Fig. 4. The toes or projections L^2 also assist in filling up this space, and may be extended for this purpose to a considerably greater distance than is shown 70 in Fig. 8. The projections V^2 , which extend from the spool-heads, serve to assist in holding the supporting-pieces upon the side of the armature against lateral displacement. The spools may be provided with intermediate 75 flanges, as indicated in Fig. 9, in order to permit the coils to be wound more readily into two sections. The joints between the sections are located beneath the shoes or plates M . 80

The mode of connecting the coils to one another forms no part of my present invention, and is not therefore described or indicated.

I make no claim herein to the described 85 method of making a sectional armature by building up the endless-core, cutting the same into sections, and then putting the sections together in a lathe and turning the core down, as this will form the subject of another application for patent to be filed by me. 90

What I claim as my invention is—

1. In a dynamo-electrical machine or motor, an armature cylindrical in outline having its coils or bobbins separated at their 95 outer circumference by iron plates set on edge upon a common base or shoe that is applied to the armature core or body, and is provided with the radially-extending plates R , through which fastening-pins a pass. 100

2. In a dynamo-electric machine or motor, the combination, with the armature-core cylindrical in outline, of transverse plates or shoes of iron applied to the outer circumference of the core between the coils or bobbins 105 and provided with a series of plates extending radially from the surface of the transverse plates and separated by free air-spaces, as described.

3. In a dynamo-electric machine or motor, the combination, with the armature-core and its bobbins, of separating-plates of iron curved to the form of the armature and provided with the radially-extending side plates to form a tray or box for a series of iron plates secured in the space between the sides by bolts or screws, as described. 110

4. In a dynamo-electric machine, the combination, with the spider-frame, the armature-core, and the separating bodies of iron interposed on the outer periphery of the armature-body between the armature coils or bobbins, of fastening-bolts passing transversely across the ends of the spider-arms and through the separating-bodies. 120

5. The combination, with the bifurcated spider-arms and the armature, of the transverse bolts at the outer-end thereof and exterior to the outer periphery of the armature core or body. 125

6. The combination, with the spider-frame and the armature supported thereon, of the 130

transverse fastening-pieces, the curved separating plates or shoes of iron resting on the armature core or body, and plates of iron supported on said shoes and having the fastening pieces or bolts of the spider passing through them.

7. In a dynamo-electric machine or motor, the combination of a spider-frame whose arms are bifurcated at their outer ends, an armature-core supported thereon, and transverse bolts K^2 , passing transversely through both sides or arms of the bifurcation.

8. The combination, with the bobbins or coils in an annular armature, of interposed sets of iron plates fastened to the sides of the armature and overlapping at their inner ends, while their outer ends diverge to follow the sides of the bobbins.

9. The combination, with the coils or bobbins in an annular armature, of the iron plates S , overlapping at their inner ends and provided at their outer diverging ends with separating-pieces of any desired material.

10. The combination, with the annular armature, of the curved iron shoes M , having the toes or projections L^2 entering beneath the armature-bobbins and provided with the iron sides M^2 , the plates of iron mounted edgewise on the shoes, the side plates of iron interposed between the bobbins, and fastening pins or bolts a .

11. The combination, with an annular armature, of a spool for the armature-coils adapted to be slipped upon the armature-core, and having a substantially straight axis or body, and key-pieces between the spool and armature-core, as and for the purpose described.

12. In an annular armature for dynamo-electric machines or motors, armature-coil spools having circumferentially-extending projections locking into the dividing or separating pieces applied to the armature-core between the bobbins.

13. In a dynamo-electric machine or motor, a pedestal of iron formed at its top into a pole-piece and provided with longitudinal exten-

sions to either side of the pole-piece and pedestal, in combination with vertical magnet-cores secured to said extensions and joined at their top by a plate that is parallel to the pedestal and extensions thereof, and is provided with a pole-piece presented to the pole-piece upon the pedestal.

14. In a dynamo-electric machine or motor, an armature spool or bobbin holder consisting, essentially, of two plates located at opposite sides of the spool-axis and separated at their edges, said plates being joined at their ends in spool heads or flanges.

15. In a dynamo-electric machine or motor, the combination, in an annular armature, of two or more bobbins wound in suitable bobbin spools or holders, compound separating-pieces of iron applied to the sides of the armature-core, and projections from the spool-heads, arranged as described, to hold the separating-pieces against lateral displacement.

16. In a dynamo-electric machine or motor, the spools T , provided with the projections V^2 , extending from the spool-heads and lapping over upon the separating-pieces applied to the sides of the armature, so as to hold said separating-pieces from lateral displacement.

17. In a dynamo-electric machine or motor, the spools T , having projections extending therefrom and interlocking with the separating masses interposed between the spools, as and for the purpose described.

18. The combination, with the fastening radial bolt or screw K , for fastening the armature-core to the spider, of the transverse bolt K^2 , passing laterally through the spider-arm directly over the bolt or screw.

19. In a dynamo-electric machine or motor, a coil-spool consisting, essentially, of two plates, W , and the heads or flanges V .

Signed at New York, in the county of New York and State of New York, this 10th day of February, A. D. 1885.
